UNITED STATES PATENT OFFICE

2,514,800

ICE CHISEL

John W. Salo, Trout Lake, Minn.

Application January 21, 1948, Serial No. 3,581

6 Claims. (Cl. 30—164.5)

1

This invention relates to novel and useful improvements in cutters for use particularly in fracturing ice.

An object of this invention is to safely transport an ice chisel, whereby the cutting surface and edges thereof are protected as well as the individuals carrying or transporting the device.

Another object of this invention is to selectively maintain the cutting edge of a chisel in the handle and the end opposite the cutting edge on the same handle.

Another object of this invention is to resiliently bias the latch means utilized in association with this maintaining mentioned in the above paragraph.

Another object of this invention is to conveniently, easily and rapidly attach and detach the cutting portion of an ice chisel from the handle portion.

A further object of this invention is to provide a simplified device of the character to be described having no objectionable protuberances on the handle portion to impede the utility of the device during ice fracturing operations.

Ancillary objects and features of novelty will become apparent to those skilled in the art, in following the description of the preferred form of the invention, illustrated in the accompanying drawing, wherein:

Figure 1 is an elevational view of the preferred form of the invention;

Figure 2 is a side view of the invention shown in Figure 1;

Figure 3 is a sectional view taken substantially on the line 3—3 of Figure 1 and in the direction of the arrows;

Figure 4 is a sectional view taken substantially on the line 4—4 of Figure 1 and in the direction of the arrows;

Figure 5 is a transverse sectional view taken substantially on the line 5—5 of Figure 4 and in the direction of the arrows;

Figure 6 is a sectional view of the handle showing the reduced portion thereof particularly and also illustrating the cutting edge of the blade seated therein, and;

Figure 7 is an exploded perspective view showing particularly the latch means used in association with the positioning of the elements shown in Figure 1.

This invention has been developed to provide a device for easily transporting an ice chisel both from the viewpoint of protecting the individual using the ice chisel and also protecting the surfaces of the cutting portion of the blade.

In order to realize this purpose the blade is se-

2

lectively attached to the handle for working operations and positioned within the handle for protection purposes. The handle generally indicated at 10 is provided with a hand engaging portion 12 and a knob 14 for limiting the travel of the hands on the work portion 12. The shank 16 of the handle has a bore or slot 18 therein with a reduced portion 20 forming a continuation of the said shank 16.

A metallic plate 22 is recessed in the shank 16 and has a slot 24 formed therein.

A blade portion 26 having a housing 28 integrally associated therewith is supplied. The said housing 28 is provided with a bore, which bore is of substantially the same dimensions as the external configuration of the reduced portion 20. The bore may be seated on the reduced portion 20 as is seen in Figure 3 for one selected position of operativeness. The terminal portion of the said blade 26 has a beveled edge 30 and adjacent this bevelled edge there is supplied a notch 32. This notch cooperates with means positioned on the handle 10 for locking purposes.

In locking the blade within the slot or bore 18, the notch 32 is engaged by an arm 34 which is pivoted in a suitable slot 36, supplied in the reduced portion 20. The said arm has an angular terminal portion 38 which seats in the notch 32 for locking purposes.

Means for resiliently biasing the pivoted arm 34 to a selected position is provided. The preferable means may be seen best in Figure 6 wherein there is disclosed a collar 40 having a resilient arm or spring 42 attached thereto. A suitable screw 44 may be used in attaching the arm directly to the reduced portion 20, if found desirable. The opposite end of the said arm or flat spring 42 is seated in a notch 46 supplied in the said arm 34. It is readily noted that the spring 42 is spaced from the surface of the reduced portion 20, whereby upon application of a force to this plate or spring 42, the arm 34 will be pivoted about the pin 48 as an axis, thereby lifting the angular extension 38 from the notch 32 for removal of the blade 26 from the bore 18.

In order to lock the housing 26 on the reduced portion 20, a pair of bayonet latch shaped notches 50 and 52 respectively are supplied in the bore of the housing 28. A lug 54 is rigidly attached to the reduced portion 20 and a resiliently biased latch keeper 56 is supplied there adjacent.

The said resiliently biased latch keeper 56 is slideable adjacent the lug 54 and is resiliently biased by means of the conventional coil spring 58. The said spring 58 seats in a recess 60 supplied in the shank 16 and has one end seated on

a shelf 62. This shelf is integral with the keeper 56 and a finger slide 64 extends through the slot 24. By this expedient the said latch keeper 56 may be selectively urged against the force of the spring 58 in accordance with the confines of the said slot 24.

In operation of the latching device utilized in association with the housing 28, the opposed lugs 54 on the said reduced portion 20 are urged into the reduced areas 50 and 52 forming bayonet shaped latch keepers and the housing 28 and handle 10 are mutually rotated. This action permits the keepers 56 to spring into the reduced portions 50 and 52 respectively in order to prevent mutual rotation of the shank and blade relative to each other. Further, this action and resultant arrangement of parts prevents relative axial movement of the blade 26 and handle 10.

If it is desirable to make the handle of a pair of substantially identical parts, the rivets or screws 70 may extend through suitable plates recessed in the handle portion for attachment purposes. This is but a matter of choice however, and if it is found desirable the handle 10 may be formed of a single piece.

Also, the said lugs 54 may be attached rigidly to plates 72 which are recessed in the said handle 10 and fixed thereto by means of the through bolts or rivets 70. This construction is preferable since the full weight of the blade 26 is carried by the said lugs 54 during the operation of the invention.

While there has been described but a preferred form of the present invention, it is apparent that variations may be made without departing from the spirit thereof. Accordingly, limitation is sought only in accordance with the scope of the following claims.

Having described the invention, what is claimed as new is:

1. An ice chisel comprising a housing forming a handle and having a bore, a blade, a latch keeper carried by said housing, means forming an opening adjacent one end of said blade operable connected with said latch keeper, an arm mounted for pivotal movement in said housing and movable in said bore for maintaining said blade in said bore, and said blade having an opening therein to seat said arm.

2. In a device for fracturing ice, a handle having a shank including a reduced portion and having a slot in said handle, a blade having a housing fixed at one end thereof, means for removably maintaining said blade on said handle including a latch keeper attached to said shank, a lug on said reduced portion adjacent said keeper, means in said housing lockingly engaging said lug and keeper, said housing fitting on said reduced portion, and means for releasably maintaining said blade in said handle including an arm pivoted to said reduced portion and a part of said arm extending through said slot, said blade and having a notch lockingly engaging said pivoted arm.

3. In a device for fracturing ice, a handle having a shank including a reduced portion and having a slot in said handle, a blade having a housing fixed at one end thereof, means for removably maintaining said blade on said handle including a latch keeper attached to said shank, a lug on said reduced portion adjacent said keeper, means in said housing lockingly engaging said lug and keeper, said housing fitting on said reduced portion, and means for releasably

retaining said blade in said handle including an arm pivoted to said reduced portion and a portion of said arm extending through said slot, said blade having a notch lockingly engaging said pivoted arm, means reacting on said handle for resiliently biasing said keeper, and a flat spring secured to said reduced portion for pivotally urging said arm.

4. In an ice chisel, a handle having a bore, a blade having an aperture adjacent the sharp end and a housing at the opposite end, means operable with said aperture and carried by said handle for retaining the sharp end of said blade in said bore, and means carried by said handle for releasably retaining said housing on said handle including a latch keeper, means slidably supporting said keeper on said handle, a spring reacting on said keeper and said handle normally pressing said keeper in a single direction, and means forming an opening in said housing engaged by said keeper for retaining said housing on said handle.

5. In an ice chisel, a handle having a bore, a blade having an aperture adjacent the sharp end and a housing at the opposite end, means operable with said aperture and carried by said handle for retaining the sharp end of said blade in said bore, and means carried by said handle for releasably retaining said housing on said handle including a latch keeper, means slidably supporting said keeper on said handle, a spring reacting on said keeper and said handle normally pressing said keeper in a single direction, and means forming an opening in said housing engaged by said keeper for retaining said housing on said handle, said handle having a reduced portion on the exterior surface thereof and said housing being of such size so as to fit on said reduced portion, the outside surface being flush with the outside surface of the part of the handle immediately adjacent the reduced portion.

6. An ice chisel comprising a handle having a longitudinal bore concentric with a reduced portion on the exterior surface thereof, a blade having a handle at one end and an aperture adjacent the opposite sharp end, means for maintaining said housing on said reduced portion including a slot in said housing, a latch keeper mounted for sliding movement on said handle and operable in said slot, the junction of said reduced portion and the remainder of said handle forming an abutment for operative engagement with said housing, and means carried by said handle and operable in said bore for locking engagement with the aperture adjacent the sharp end of said blade to retain said blade within said bore, said last-mentioned means including an arm mounted for pivotal movement on said handle, a flat spring carried by said reduced portion and slideable within said housing when said housing is disposed on said reduced portion, said spring reacting on said arm opposing the operation of said arm.
